John Bailey & William C. Bailey, Farmington
State of Maine,

Letters Patent

The schedule referred to in these Letters Patent, and making part of the same containing a description in the words of the said John Bailey and William C. Bailey, themselves of their improvement in a machine called a Kitchen Boiler.

To all to whom these presents shall come: Be it known that we John Bailey and William C. Bailey, both of Farmington in the County of Kennebec and State of Maine have invented a new and useful and improved machine called a Kitchen Boiler for the purpose of heating water for family use; and that the following is a full and accurate description of the said machine in its several parts. That part which is properly called the boiler consists of a hollow cylinder of about twelve inches in length and five or six inches in diameter which is of copper or some other metallic substance of at least equal hardness and density and is so constructed as to be firm, strong, and water-tight. The cylinder in regard to its shape may be round or it may have one or two flat surfaces and the other circular as may be found most convenient in adapting it to the place where it is to be situated but that part of its surface which comes in contact with the fire is always to be circular; it is placed in a cavity made for its reception in the back of a common kitchen fireplace which cavity in most cases is easily made by removing a few bricks especially where there is a false back. The front end of the cylinder is not to project forward any further than to be even with the rest of the back of the fireplace of

which it becomes a component part, and if it were placed inward by such farther than the surface of the brick, provided the bricks at the bottom of it are tapered down a little it would receive the heat of the fire quite as well, and would be less liable to external injury, though the back part of the cylinder there is a tube inserted, which is from one to two inches in diameter of a substance similar to that of the boiler and made perfectly firm and tight at the place of its insertion. This tube is not of any specified length but must always be long enough to reach through the back of the fire place or one of its chimneys and enter into a cistern which is then placed and which is to contain the water to be heated for use.

The tube passes from the boiler and enters into the cistern ^{about} half way from the bottom to its top in a straight line; or it may incline, so as to enter nearer the bottom in this case, the heat being thus more readily diffused by its ascent, through the whole of the water which it contains, when there is no convenient place to set the cistern in the rear of the fire place it may be set by the side of one of the chimneys; in this case the tube which communicates from it to the boiler must be inserted into one end of the boiler instead of its side as above described. The cistern consists of a box made of thick boards or planks with square corners, and is about two feet long, a foot and a half wide and a foot and ^{half} high. The whole is fully and firmly framed together so as to be strong and proof against leaking, there is also a wooden cover attached to it which is hung with hinges and can be shut down so close as to prevent any steam from escaping out of the box except it be through a hole made for that purpose. The cover of the cistern being raised up cold water is turned in at the top until it is nearly filled, but the water must never stand much higher in the cistern than the top of the

boiler in the chimney, lest by its pressure it should burst the boiler. When the cistern is first filled with water the boiler is full of air and cannot therefore be immediately filled with water through the medium of the connecting tube, but as soon as a moderate degree of heat is applied to the surface of the boiler the air within is expanded and is at once expelled through the tube and water is let in to supply its place, the boiler is set into the back of the fire place about ten or twelve inches above the hearth, and when a moderate fire in the usual manner is kindled below it, if it be only enough to boil a tea kettle or to make a room comfortably warm in cold weather it will in a short time render the water in the cistern through the boiler and the tube sufficiently hot for washing clothes, dishes or any ordinary purpose for which hot water is usually wanted, Here it will be perceived that besides the conveniences there is a great saving of fuel, for without any extra fire upon the hearth there may be from six to a dozen gallons of water always hot and ready for family use, the hot water may be slipped out from the top of the cistern, the cover being raised up for that purpose or it may be drawn off by a cock or faucet inserted toward the bottom as may be most convenient. There is still another use to be made of the kitchen boiler, which has not yet been named, that is, of raising and collecting steam, which when properly applied will answer several purposes of cooking as that of potatoes in particular as well as many other things when the steam is thus to be used a distinct apparatus is necessary.

First a wooden slider is let down near the mouth of the tube across the cistern from top to bottom which slider divides the water in the cistern into two sections. This is done to diminish the quantity of water to be set on boiling in the act of steaming. The reason of this is obvious, because the smaller the quantity of water the less

heat will be required to convert it into vapour,

The boiler may be stationary and remain in its place provided a hole is bored through it, so that the water in both sections can communicate with each other in ordinary easy, but when steaming is going on it must be stopped, with a plug, whereby all such communication is prevented, then the cover of the cistern is shut down tight and a hole is bored through either the end side or cover of the cistern as most convenient, through which a pipe of any suitable dimension, is inserted and which conveys the steam to another appropriate vessel, which is to receive the article for cooking, to accelerate the steam process it will be necessary to increase the fire a little which comes in contact with the surface of the boiler above the hearth, The steam pipe may be rendered useful in another respect besides that for cooking, for it may be employed to convey away any excess of steam which may at any time arise from the cistern in consequence of too much heat, and which might otherwise be troublesome in the room, care is to be taken to keep so much water in the cistern, as to fill the boiler, lest it should receive injury from the heat of the fire The dimensions of the above described machine & in its several parts may be made larger or smaller according to the quantity of water intended to be heated, Dated at Washington aforesaid this 25th day of April anno Domini 1835,
